CLAIM

The ornamental design for sports sunglasses as shown and described.

DESCRIPTION

1. Sports sunglasses
- 1.1 : Perspective
- 1.2 : Perspective
- 1.3 : Front
- 1.4 : Back
- 1.5 : Left
- 1.6 : Right
- 1.7 : Top
- 1.8 : Bottom

Fig. 1.1 is a perspective view of sports sunglasses showing my new design; Fig. 1.2 is another perspective view thereof; Fig. 1.3 is a front elevational view thereof; Fig. 1.4 is a back elevational view thereof; Fig. 1.5 is a left side elevational view thereof; Fig. 1.6 is a right side elevational view thereof; Fig. 1.7 is a top plan view thereof; Fig. 1.8 is a bottom plan view thereof; The dash-dash broken lines in the drawings depict portions of the sports sunglasses that form no part of the claimed design.
